UNITED STATES PATENT OFFICE.

ARTHUR SCHERBIUS, OF BERLIN, GERMANY.

DIRECT-CURRENT MACHINE.

1,352,920.

Specification of Letters Patent. Patented Sept. 14, 1920.

Application filed November 25, 1914. Serial No. 874,061. Renewed February 4, 1920. Serial No. 356,125.

To all whom it may concern:

Be it known that I, ARTHUR SCHERBIUS, a subject of the German Emperor, residing at Berlin, Charlottenburg 9, Germany, have 5 invented certain new and useful Improvements in Direct-Current Machines, of which the following is a full and clear specification.

Commutation plays an important part in 10 the proper operation of direct current machines.

As the brush slides over the commutator segments, the current in the coils connected with the segments, which had a certain direction before the connection of the segments by the brush, must flow in the opposite direction after the brush has passed.

As is generally known, this commutation process is improved by letting the coils during the short circuiting by the brush rotate past auxiliary fields which produce a rotation tension in the coils, which causes the current's reversal. These fields must be made of just the right size to insure that the 25 current flowing from the segments to the brush passes through the zero point as exactly as possible at the moment the brush is leaving the corresponding segment. If the current has either not yet become zero, or 30 has already commenced flowing in the opposite direction a spark occurs as the brush leaves.

The object of the present invention is to avoid the formation of sparks at the commutator, even if the commutating field is not of the exact magnitude necessary.

The invention is illustrated in the accompanying drawing, in which—

Figures 1 to 4 show assembled diagrammatic views of the armature winding, commutators and check valve devices for controlling the commutated current.

Figs. 5 to 7 serve to illustrate the operations more in detail.

Fig. 8 represents a particular commutating device.

Figs. 9 and 10 represent particular modifications of the form shown in Figs. 8 and 5 respectively.

In Figs. 1 to 4 a direct current motor is shown, of which p are its field poles and a its armature winding. The armature winding is coupled with two commutators k_1 and k_2 , which have conducting segments spaced 55 apart by the broad insulation pieces d . The

individual parts of the armature winding are each connected at their ends to the different segments of both commutators, as shown in the drawing. The brushes b_1 , b_2 , b_3 , b_4 , are narrower than the insulation piece d , so that none of the brushes can short circuit two sections of the same commutator. The short circuit of an armature winding can only occur in common over the two brushes and their connecting conductors, and the brushes are located so relatively to the field poles that a suitable commutating field is produced and proper commutation occurs.

In these connecting conductors are arranged rectifiers (for example mercury vapor rectifiers) which in known manner possess the property of letting through electric current only in one direction while preventing the passage of current in the other direction.

The combining of such electrical check valves, which are arranged in the manner of rectifiers, with the above described form of commutator, forms the basis of the invention. These check valves in the present use do not have the purpose of rectifying the current, but have the sole purpose of improving the commutation and thus, while to be sure, they have certain physical properties in common with check valves employed as rectifiers, the employment of these properties is different.

The commutating process can be seen from Figs. 1 to 4, which show a machine in the different commutating stages. The valves in which the current is flowing are shown shaded. As will be seen in Fig. 1, the current flows only in the valves v_2 and v_4 , and in the brushes b_2 , and b_4 , while the brushes b_1 , and b_3 and valves v_1 , v_3 , are without current. When the armature turns as indicated by the arrow, the position indicated in Fig. 2 will be assumed. In this position the valves v_1 , and v_3 , are also supplied with current. Thus the section h of the armature winding is short circuited. By rotation of the armature wires in the magnetic field there is, moreover, produced in this portion of the winding at the moment of short circuiting an electromotive force whose direction is indicated by the double arrow e . The brushes are shifted as in ordinary direct current motors, that is, contrary to the direction of rotation, and the electromotive force 105 110

is directed against the current i previously flowing in the armature portion h . It thus has a tendency to neutralize the current in the valves v_2 , and v_4 in order to drive it 5 through the valves v_1 , and v_3 . At the end of this period, the current i in the valves v_2 , and v_4 , drops to zero and is completely transferred to the valves v_1 , and v_3 . After the current i has become zero no more current can flow as the valves are check valves. 10 While the commutator tension e operates, the armature moves from the position shown in Fig. 2 into the position shown in Fig. 3, from which figure it can be seen that the current i now flows only in g_1 and g_3 . The change from Fig. 3 to Fig. 4 occurs without switching operations in the valves. 15

The brushes b_2 , and b_4 rest without sparking upon the insulated part of the commutator, as currents do not flow in them. In 20 the further rotation, the switching is repeated in the same manner as above described. After a short time the valves v_2 , and v_4 are traversed by current, and the 25 currents in the gas contacts v_1 , and v_3 are interrupted.

Slight differences of tension at the advance edges of the brush are in general of less danger than the presence of a current 30 where the brush is leaving. Greater difference in potential even at the forward edge can, however, be injurious to the commutator under bad commutating conditions. In order to fully avoid sparking also on the 35 forward edge, the commutation must be so arranged that before the projection of a brush upon a segment, a tension is produced in the armature winding connected with this segment, which will create a current against 40 the valve operation, so that the flowing of a current, that is, the passage of a spark, to the projecting edge is avoided.

This relation may now be observed in 45 more detail with relation to Figs. 5 and 7. Figs. 5 to 7 show sections of the commutator and the winding of a motor (according to Figs. 1 to 4) and especially that part which operates in the vicinity of the positive brush. The poles marked S and W 50 constitute commutating fields.

The negative brushes are omitted for the sake of clearness.

The brush b_1 in Fig. 5 is just at the point of passing on to the segment l_1 . If a strong 55 commutating electromotive force is already present in the armature coil, this might produce a spark between b_1 , and l_1 , and cause a high specific current load in the narrow projecting edge. In order to avoid this, a 60 tension in the direction of the brush b_1 is produced in the armature winding w before the projection of the edge of brush b_1 over l_1 . This tension has the tendency of producing in the conductor g_1 a current in the 65 direction of the arrow p_2 . On account of

the check valve action of the valve v_1 , such a current can not flow however, so that likewise a spark and over load on the edge of the brush can not occur.

The field in the auxiliary pole N is directed against the real commutating field S. After the brush b_1 has extended farther over on l_1 , then the above described operation of the commutating pole S begins which gradually forces the current from v_2 over 70 to v_1 , as shown in Figs. 6 and 7. In the armature position of Fig. 6, the current flows in both conductors g_1 and g_2 , whereas in Fig. 7 it has already ceased in the conductor g_2 . 75

Fig. 8 shows an embodiment of an auxiliary pole arrangement by the aid of which commutation can be carried out in simple manner, as required according to the above explained theory.

In Fig. 8, h is an auxiliary pole which carries the commutating winding b . This is so strong that it compensates the ampere turns of the armature in known manner and produces beyond this a field for commutation. 85

In order to avoid the occurrence of a tension at the brushes as they leave the segments, the auxiliary pole is provided with a recess n , in which a second winding c is disposed. This has the purpose of weakening 95 the forward auxiliary field and strengthening the rear field. The winding c can be weak with respect to b as the electromagnetic forces which form the real auxiliary pole field are small as compared with the 100 total ampere turns exciting the armature ampere turns. As the current of the winding c must change in direction with the direction of rotation of the motor, it is desirable to connect these in series with the field 105 winding, in case the motor is reversed by reversing the field. This is shown in Fig. 9, in which $p-p$ represents the field poles having the field windings x_1-x_2 ; h_1-h_2 are the auxiliary poles, carrying the commutating windings z_1-z_2 and also the windings c_1-c_2 respectively. In this figure the motor has shunt excitation, which is connected to the main +, - by way of change-over switch u and rheostat r . The switch serves 110 for reversing the field whereas the rheostat serves for controlling same. The shunt exciting current flows from + pole to - pole 115 successively through four coils, x_1 , c_1 , c_2 , x_2 . The main circuit is independent thereof and flows from + pole, z_2 , z_1 , v_1 , v_2 , b_1 , b_2 , armature, b_3 , b_4 , v_3 , v_4 , - pole. Thus if the direction of rotation is reversed by throwing switch u into the other position, the main current flows in the same direction in the valves, 120 brushes, armature and in the commutating windings z_1-z_2 of the auxiliary poles, whereas in the exciting coils and in the small auxiliary coils c_1-c_2 it is reversed. If the 125 motor runs in but one direction then it is 130

sufficient to provide a single piece auxiliary pole which corresponds in size and position with the left hand half of the auxiliary pole shown in Fig. 5. The right hand part can, 5 in this case, be omitted. This is shown in Fig. 10. In this case a series motor connection is shown. Only the main current passes through the auxiliary windings in the following sequence: + pole field coils x_1 , x_2 , 10 auxiliary coils z_1 , z_2 , valves v_1 , v_2 brushes b_1 — b_2 , armature, brushes b_3 — b_4 , valves v_3 — v_4 , — pole.

As distinguished from the use of an ordinary commutator, the connections have important advantages, as will be seen. One 15 can construct the commutator with a smaller number of segments than is possible in the ordinary commutator, which is obvious from the following explanation.

20 One can produce a certain maximum tension between two segments of the ordinary commutator. The limits of the tension are on the one hand determined by that tension which can not possibly pass the insulation, 25 and on the other hand they are determined by the limit of tension up to which one can still commutate without sparks. As with the ordinary commutation means one can only compensate a definite percentage of the re- 30 action tension occurring in the commutation, the commutation will naturally become more difficult as the magnitude of the reaction tension between two segments becomes greater. It is, therefore, not directly pos- 35 sible with an ordinary commutator to increase the tension between two segments by increasing the insulation material as much as desired, because even if the increased layer of insulation resists the open spark 40 tension, still the objectionable tension which can not be neutralized by exact commutation devices becomes so considerable that the commutator is destroyed. Therefore, if the 45 actual commutation process is entirely re- moved from the commutator, so that the in- 50 terruption of current or a closing of the current in the same never occurs and so that the same only opens or closes contacts which are without current or tension, one can in- 55 crease the tension between two brushes per cm. of commutator surface, further than is possible in the ordinary commutator. One can also have fewer segments, because be- 60 tween two segments as high a tension as de- 55 sired can be produced, if one makes the intervening insulation layer sufficiently thick. As one is less limited in the breadth of the segments, the breadth of the brushes can also be increased and as much current can be 65 taken from a commutator as is permissible with respect to its cooling outer surface. Especially are high tension commutators reduced in size over the previous forms, in this way.

65 It is obvious to anyone skilled in the art

that though I have illustrated and described as an example, preferred forms of the embodiment of my invention, it may be applied to any type of dynamo electric machine, requiring and being provided with means for 70 commutation irrespectively of the particular nature of such means.

I claim:

1. A direct current dynamo electric machine, comprising in combination an armature having a closed winding, two commutators having electrically conductive segments alternating with insulation pieces and connected alternately to the individual ends of the armature winding, a pair of brushes operating on each commutator, narrower than said insulation pieces, connections between the two brushes of a single pole, means for producing a commutating field, sharply defined in the direction of the armature conductors which first enter the commutating field, for over-commutating the current in the armature coils which are short-circuited by the brushes, and means for preventing current from flowing in a direction opposite 80 to that in which the normal commutating current flows through said connections.

2. A direct current dynamo electric machine, comprising in combination an armature having a closed winding, two commutators having electrically conductive segments alternating with insulation pieces and connected alternately to the individual ends of the armature winding, a pair of brushes operating on each commutator, narrower than said insulation pieces, connections between the two brushes of a single pole, means for producing a commutating field sharply defined in the direction of the armature conductors which first enter the commutating field, for over-commutating the current in the armature coils which are short-circuited by the brushes and electric check valves inserted in said connections for preventing current from flowing in a direction opposite to that in which the normal commutating current flows through said connections.

3. A direct current dynamo electric machine comprising in combination an armature having a closed winding, an auxiliary field pole with two teeth having a winding between said teeth, two commutators having electrically conductive segments alternately connected to the individual ends of 115 the closed armature winding, insulation pieces between said segments, brushes operating on said commutator and narrower than said insulation pieces, said auxiliary field pole producing over-commutation of 120 the current in the armature coils short-circuited by the brushes, connecting conductors between the two brushes of a single pole, and electrical check valves inserted in said conductors for preventing current from 125 130

flowing in a direction opposite to that in which the normal commutating current flows through said conductors.

4. A direct current dynamo electric machine, comprising in combination an armature having a closed winding, an excitation field winding, an auxiliary field pole with two teeth having a winding between said teeth, connected in series with said excitation winding, two commutators having electrically conductive segments alternately connected to the individual ends of the closed armature winding, insulation pieces between said segments, brushes operating on said 10 commutators and narrower than said insulation pieces, said auxiliary field pole producing over-commutation of the current in the armature coils short-circuited by the brushes, connecting conductors between the two brushes of a single pole, and electrical 20 check valves inserted in said conductors for preventing current from flowing in a direction opposite to that in which the normal commutating current flows through said conductors.

ARTHUR SCHERBIUS.
